UNITED STATES PATENT OFFICE.

JOHN W. LESLIE, OF EVANSTON, AND ROBERT H. FULTON, OF CHICAGO, ILLINOIS,
ASSIGNORS TO SIGNODE SYSTEM, INC., OF CHICAGO, ILLINOIS, A CORPORATION OF
DELAWARE.

SEAL.

Application filed December 6, 1922. Serial No. 605,163.

Our invention relates to a seal which consists of a metal strip adapted to be formed into a loop and to be secured in such manner that it cannot be opened and reclosed except with the utmost difficulty, and with the certainty that such violation of the seal will be apparent or readily detectable. Devices of this character are adapted to be employed for a great variety of sealing purposes, as, for instance, in connection with car doors, other doors, cans, boxes, trunks, shipping cases, bags, etc.

Our present invention provides a metal seal of new and unique construction, which is adapted to be threaded through and upon itself to form a loop and to be secured in such a manner that the loop closely "hugs" the elements (for instance, the pin and lug of an ordinary form of car door fastener) through which the seal passes, and renders practically inaccessible those portions of the seal to which access must be had by any person desiring to open and reclose the seal.

When properly applied in the manner hereinafter set forth, the seal of our invention comprises a free end of substantial length, which provides ample space for such data as the seal number, initials of a railroad company or shipper, etc.

Prior to being used, the seal of our invention is, or may be, substantially identical with the seal shown in co-pending application of Robert H. Fulton, Serial No. 558,719, filed May 5, 1922. All patentable subject matter common to this case and the aforesaid co-pending application will be claimed herein, the claims of said co-pending application being limited to features of improvement not shown or claimed herein.

In the accompanying drawings illustrating our invention:—

Figure 1 is a view in perspective of the seal of our invention as it appears before it has been looped and crimped;

Figure 2 is a fragmentary view in perspective, illustrating the reverse side of one end of the seal shown in Figure 1;

Figure 3 is a fragmentary view in perspective of portions of a well-known type of car door fastener, this view illustrating our improved seal as it appears in the course of its application to such a car door fastener;

Figure 4 is a view in perspective illustrating the seal of our invention, as it ap-

pears when finally applied to the car door fastener;

Figure 5 is a fragmentary view partly in section, but illustrating in elevation those portions of the sealed joint which closely hug the door fastener when the seal is applied as shown in Figure 4; and

Figure 6 is a transverse section taken on the line 6—6 of Figure 5.

Similar characters of reference refer to similar parts through the several views.

The seal of our invention comprises an integral and preferably ductile metal strip 11, which at one end is provided with lateral wings 12—12 which have been turned away from the strip proper and toward each other as is clearly illustrated in Figures 1 and 2. Two parallel slits 13—13 are formed in the winged end of the strip and the web 14, which lies between these slits, is raised above the plane of the rest of the strip to permit and facilitate the formation of the sealed loop in the manner presently to be described.

That end of the metal strip which is to be threaded through the slits 13—13 is conveniently pointed, as at 15, and apertured as at 16 to receive a seal carrier. Ordinarily, the pointed end of the strip will have certain data, such as a seal number and initials lithographed or impressed thereon, as illustrated at 17.

As seals of the type to which our invention relates are very commonly used in connection with fasteners of the type employed in conjunction with railway car doors, we shall herein illustrate and describe the application of our improved seal to such a fastener. However, it is to be understood that the use of our seal is in no way restricted to car door fasteners.

In Figure 3 we have illustrated certain portions of a well-known type of car door fastener. In this figure, A indicates the fastener element which is usually applied to the door frame, and B illustrates the hasp which is usually carried by the door. The hasp B is provided at its free end with a slot C to receive the horizontal lug D, which forms part of element A. Lug D is in turn provided with an opening E for the reception of the lower end of the pin F. Pin F is provided with a slot G, which, when the pin is in its locking position, registers with a corresponding slot H in the fixed lug I,

- which forms part of element A. It is, of course, unnecessary to illustrate the fastener in all of its detail, since our invention is not concerned with details of car door fastener construction. The specific type of car door fastener herein illustrated is to be regarded as being merely representative of the many different devices with which our improved seal may be employed.
- 10 In applying the seal of our invention to a fastener of the type shown in Figures 3 and 4, the pointed end of the seal is threaded through the slots G and H and is then passed through slots 13-13 and under web 14 to form a loop in which the extremities of the seal strip extend in opposite directions, as distinguished from the ordinary car seal loop in which the extremities extend in the same direction. The seal loop is drawn 20 tightly up against the fastener elements F and I, and the seal is closed by a distorting operation, which is preferably a crimping operation performed in accordance with the method of Flora U. S. Patent No. 1,038,108, dated September 10, 1912, and is accomplished by means of a sealing or crimping tool substantially like the tool shown and described in Flora U. S. Patent No. 1,038,109, dated September 10, 1912.
- 30 In closing the seal by means of a device of the type shown in the Flora patent last above-mentioned, the jaws of the sealing tool are applied to the lateral edges of the wing portion of the seal, the sealing tool serving 35 simultaneously to crimp that portion of the strip which passes under web 14 into interlocking engagement with said web and with the wings 12-12. The slots 13-13 define the points where the jaws of the sealing tool 40 are to be applied, and in a measure facilitate the crimping operation. Figures 4, 5, and 6 illustrate the seal as it appears after the performance of the crimping operation just described.
- 45 The wings 12-12 materially strengthen the crimped joint in addition to permitting the finished joint to be of minimum width, notwithstanding the fact that the slits 13-13 are somewhat longer than the width of the 50 seal portion which is passed therethrough.
- In applying the seal, the loop thereof is drawn tightly against those portions of the fastener through which the seal passes. Consequently, the sealed joint "hugs" the 55 fastener, with the crimped-in portions of the wings and embraced metal inaccessible to anyone desiring to tamper with the seal. This is a very important advantage afforded by the present invention. Our 60 present seal also possesses the advantage that it affords a long free end adapted to carry the seal number, initials, or other suitable indicia. The seal is cheap to construct, may be readily applied to a fastener 65 or the like, and may be effectively closed by

a single operation of the type of crimping tool hereinbefore mentioned. Other advantages of our improved seal will be apparent to persons familiar with the art to which our invention relates.

Having thus illustrated and described a preferred embodiment of our invention, we do not limit ourselves to the precise construction and arrangement of parts herein shown, and described, but wish to cover 75 any equivalent construction falling within the scope of the appended claims.

What we claim is new and desire to secure by Letters Patent of the United States is:—

1. A seal comprising a metal strip provided at one end thereof with lateral wings, which together with said strip end constitute a sleeve, there being a pair of transverse slits in the aforesaid end of the strip, the metal between said slits being offset from the adjacent metal and away from said wings.

2. A seal comprising a metal strip provided at one end with lateral wings, there being a pair of transverse slits formed in the winged end of said strip, the metal between said slits being offset from the adjacent metal and away from said wings, said slits adapted to have the opposite end of the strip pass therethrough.

3. A seal comprising a metal strip provided at one end with lateral wings, there being a pair of transverse slits formed in the winged end of said strip, said slits terminating short of the lateral edges of the said winged end of the strip the metal between said slits being turned backwardly away from said wings, said wings being turned away from the plane of the adjacent metal and toward each other.

4. A seal comprising a metal strip pointed at one end and provided at the other end with a pair of lateral wings, a pair of parallel transverse slits formed in the winged end of the strip, said slits terminating short of the lateral edges of said winged end and being adapted to have the pointed end of the strip pass therethrough, the metal between said slits being pressed away from the plane of the adjacent metal and away from said wings to provide an offset web, said wings being turned away from the plane of the strip and toward each other substantially as and for the purpose set forth.

5. A seal comprising a metal strip provided at one end with lateral wings, there being a pair of transverse slits formed in the winged end of said strip, said slits being adapted to have the other end of the strip pass therethrough, the metal between said slits being pressed away from the plane of the adjacent metal and away from said wings to provide an offset web.

6. A metal strip provided at one end with a pair of transverse slits, the other end of the strip being passed through said slits to form a loop wherein the strip ends extend in opposite directions, that end of the strip which is provided with the slits as aforesaid being provided with lateral wings which are turned away from the adjacent metal and toward each other, that portion of the metal of the winged end of the strip which lies between said slits being crimped into interlocking engagement with said wings and with the metal which extends through and between said slits.
- 10 7. In combination with a pair of juxtaposed members forming part of a fastener, a seal strip passing through said members, said seal strip being provided at one end with a pair of transverse slits, the other end of the strip being drawn through said slits to provide a loop which closely hugs said fastener members, and wherein the strip ends extend in opposite directions, the metal between said slits being crimped edgewise into interlocking engagement with the strip metal which extends through and between said slits, the inwardly crimped edges of the metal lying closely adjacent the fastener members hugged by the seal loop.

- 15 8. In combination with a pair of juxtaposed members forming parts of a fastener, a seal strip passing through said members, said seal strip being provided at one end with lateral wings and transverse slits which terminate short of the lateral edges 30 of said winged end, the other end of the strip being passed through said slits to form a loop which closely hugs the fastener members aforesaid, the strip ends extending in opposite directions, said wings being turned 35 inwardly toward the interior of the loop and toward each other, said wings, the web between said slits, and the metal which extends through and between said slits being crimped simultaneously edgewise into interlocking relation.

- 20 9. A seal comprising a metal strip provided at one end thereof with lateral wings which are turned away from the adjacent metal and toward each other, there being a pair of transverse slits in the aforesaid end of the strip, the metal between said slits being offset from the adjacent metal and 40 away from said wings.

25 In witness whereof, we hereunto subscribe 50 our names this 1st day of December, 1922.

JOHN W. LESLIE.
ROBERT H. FULTON.
